CLASP OR RELATED ARTICLE

John F. Adams, Washington, D. C.

Application July 8, 1941, Serial No. 401,515

1 Claim. (Cl. 24—252)

This invention relates to clasps or related articles and particularly to clasps of such character that they accommodate themselves to or compensate for variations in the thickness of articles gripped thereby.

Among the objects of the present invention is the production of clasps of simple and economical structure which clasps are structurally produced to accommodate themselves to variations in thickness of articles gripped thereby without loss of effective gripping action.

Still further objects include the production of clasps peculiarly adapted to holding seaweed or similar articles.

Other and further objects and advantages of the present invention will appear from the more detailed description set forth below, it being understood, however, that this more detailed description is given by way of illustration and explanation only, and not by way of limitation, since various changes therein may be made by those skilled in the art without departing from the scope and spirit of the present invention.

In connection with that more detailed description, there is shown in the accompanying drawing in

Figure 1, a plan view of a clasp produced in accordance with the present invention; in

Figure 2, a reverse plan view of the clasp of Figure 1; in

Figure 3, a transverse section on the lines 3—3 of Figure 1; in

Figure 4, a front elevation of the clasp of the present invention; and in

Figure 5, a perspective view of the clasp.

As illustrated in the drawing, the present invention is particularly concerned with clasps and particularly clasps in which jaw members are utilized for gripping materials or products where the gripping action is exerted even though the materials clasped may vary substantially in thickness over the portion of such material clasped by the clasps of the present invention. Particularly as illustrated, the clasps of the present invention are concerned with jaw members pivotally connected together, where one of the jaw members is of substantially heavy and rigid material while the coacting jaw member is desirably light, flexible and springy. Such weighted clasps due to the heavy jaw member present, may be used to retain desired articles submerged in liquid, as for example, in retaining seaweed in aquaria in the position desired.

Referring to the clasp as illustrated in the drawing, two jaw members 1, 2 are provided

5 pivotally connected together as at 3. Desirably the jaw member 1 is heavy and rigid and may be substantially shell-shaped as indicated, while the coacting jaw member 2 is desirably of flexible and springy material. For such purposes any desired materials may be employed but preferably jaw member 1 is made of lead or lead alloy from which it may be cast in the desired shape, while jaw member 2 is of flexible and spring sheet metal or may be of flexible springy plastic material, sheet metal being desirable.

One of the jaw members is provided on its under surface in this case jaw member 1, with lugs or projections 4, 5 provided with openings or perforations 6 therein, for reception of the pivot or pintle 7.

10 The other jaw member as illustrated jaw member 2, may be slit to provide tongues 8, 9 struck up from the jaw member 2 so that the pivot or pintle 7 may extend through the openings thus formed, the tongues 8 and 9 pressing against such pivot or pintle 7 to hold the jaw member 2 in position.

15 The jaw member 1 may be provided with a base 10 while the jaw member 2 has an end 11 extending beyond the pivot joint, the base 10 and handle 11 serving as ends that may be gripped by the user of the clasp.

20 The arcuate extended jaws 12 and 13 form a substantial surface for engagement with articles to be clasped. Desirably in order to enable the jaws to adjust themselves to varying thicknesses of material gripped, one of the jaw members, as for example, member 2 is provided with a series 25 of spring fingers or bifurcations 14 which may be formed by cutting through the material 2 at the gripping edge thereof for a substantial distance from the edge of the jaw 2. A series of closely contiguous spring fingers of this character spread over all or a portion of the gripping edge of jaw 2 enable the jaw to present a continuous gripping area throughout its arcuate portions while the spring fingers adjust or adapt themselves to varying thicknesses of the material gripped. Desirably the fingers 14 are flexed 30 as shown at 15 so that only the extreme outer edges thereof contact against the corresponding portion of jaw 1. The spring fingers may be given any desired contour for special gripping action to suit particular cases.

35 Desirably the heavy jaw member 1 is cut away to provide a concave portion 17 to provide an enlarged space within and between the jaws to accommodate ends of material gripped by the clasp and to reduce the amount of metal in the ma-

terial. And further desirably the jaws are spring pressed to maintain them in gripping relation for which purpose the base of the jaw member 1 may be cut away to provide a seat 18 in which one end of a coil spring 19 is seated, while the other end of the coil spring 19 is positioned by an ear 20 struck up from the handle portion 11 of the jaw member 2.

Clasps of the present character are simple in structure and economical to manufacture. The weighted jaw member enables the clasp to remain submerged in liquid as in the water of an aquarium while the gripping jaws hold any desirable material such as seaweed in position, and the spring fingers of the jaw adjust themselves to accommodate any varying thickness of the material gripped by the clasp, as for example, when the stems of seaweed are gripped and held in position.

Having thus set forth my invention, I claim:

A clasp comprising a pair of jaw members pivotally connected together, one jaw member being metallic, heavy and rigid and serving to weight the clasp, the heavy jaw member being concave on that portion facing the other jaw member, the other jaw member being of a unitary sheet-like construction and flexible and springy, and provided along its outer gripping edge with a series of inwardly extending slits forming a multiplicity of flexible, elongated, fingers, a portion of which lie in the plane of the jaw member of which they form a part, and a spring member carried by said jaws to urge the fingers of the flexible jaw toward the heavy jaw member, thereby forming a substantially continuous gripping edge compensating for variations in thickness of material gripped between said jaws.

JOHN F. ADAMS.
